his ATTORNEY

UNITED STATES PATENT OFFICE.

SAMUEL HAMMER, OF BROOKLYN, NEW YORK.

METAL RECEPTACLE.

Application filed October 19, 1926. Serial No. 142,541.

This invention relates to metal receptacles, and more particularly to mail boxes or receptacles such as are usually provided in apartment houses, hotels and other large buildings for the collection of mail addressed to tenants residing therein, such for instance as is illustrated and described in my pending application filed May 13, 1924, Serial No. 712,945.

10 It is one of the objects of my present improvements to provide a part of the mail box structure with one or more slots therein corresponding to the number of tenants to be served and a name card holder associated 15 with each slot at the rear side thereof, and the receptacle wall being provided with integrally formed means for directing a card from the front side of the wall into said holder.

20 My invention is more particularly designed for use and application in connection with that type of receptacle wherein the receptacle is provided at one side of the mail receiving compartments with a supplemental 25 compartment with which speaking tubes from the several apartments are connected. The front open side of this supplemental compartment is closed by a metal panel, and it is a further object of my invention 30 to provide this panel, in addition to the name card holding means above referred to with means for detachably supporting switch units operated by suitable push buttons mounted in the panel whereby the circuit of a call bell or buzzer is closed.

35 It is a further important object of my invention to provide such name card holders and switch unit supporting means as integral parts of a common reinforcing plate 40 permanently secured to the rear side of the panel which may be fabricated at relatively low cost and in which provision is made for the application of additional switch units from time to time.

45 With the above and other objects in view, the invention consists in the improved metal receptacle and in the form, construction and relative arrangement of the several parts as will be hereinafter more fully described, 50 illustrated in the accompanying drawings, and subsequently incorporated in the subjoined claims.

In the drawings, wherein I have shown one simple and practical embodiment of my

present improvements, and in which similar reference characters designate corresponding parts throughout the several views,—

Figure 1 is a fragmentary front elevation of a metal mail box or receptacle provided with my invention;

Fig. 2 is a rear elevation on an enlarged scale of the metal panel removed from the box structure showing the form and construction of the name card holders and the switch unit supporting means;

Fig. 3 is a horizontal section taken on the line 3—3 of Fig. 2;

Fig. 4 is a similar sectional view taken on the line 4—4 of Fig. 2, and

Fig. 5 is a detail vertical section taken on the line 5—5 of Fig. 2.

Referring in detail to the drawings, the body of the box or receptacle may be of similar construction to that shown in my co-pending application and is provided with the usual front plate indicated at 5 having suitable vertically spaced openings therein closed by the doors indicated at 6 and 7 respectively, and through which the mail is inserted into and removed from the several compartments of the receptacle. At one side of this series of mail receiving compartments, the box structure is provided with an additional supplementary compartment with which speaking tubes leading from the several apartments of the building are adapted to be connected. The front plate 5 is provided with an additional opening 8 therein which extends over the entire length of this supplementary compartment. This opening is closed by a metal panel shown at 9 which may be detachably fixed at its upper and lower ends as by the screws 10 to suitable means provided on the box structure. At its upper end the panel 9 may be provided with a series of ornamental shaped apertures 11 therein through which the voice sounds may pass.

The panel 9 is preferably formed from sheet brass, the front surface thereof being given a satin finish, and for the purpose of reinforcing this panel, I secure to the rear side thereof the reinforcing plate generally indicated at 12 which extends substantially over the entire length and width of said panel. At its upper and lower ends, this reinforcing plate is spot-welded to the panel 9 as indicated at 13 and the upper

end of the plate is provided with an opening 14 therein surrounding the series of openings 11 in the panel.

Along its opposite side edges and extending the full length thereof, the plate 12 is provided with the flanges 15 which project rearwardly from said panel at right angles to the plane thereof. Between these flanges 15 the body of the reinforcing plate is provided with a plurality of equi-distantly spaced horizontal extending sections 16 which are integrally connected along their longitudinal edges with the body of the plate and are offset from the plane thereof, and thereby spaced from the rear face of the panel 9. These horizontal sections 16 of the reinforcing plate at one of their ends terminate closely adjacent to one of the flanges 15, while their other ends are spaced an appreciable distance from the other of the flanges 15, the intervening body portions of the plate 12 being cut out to provide the openings 17 therein.

The parts 18 of the reinforcing plate 12 between the offset sections 16 which integrally connect the side flanges with each other are each centrally provided with a circular opening 19 and also with the rectangular slots 20 laterally spaced from the flanges 15.

The panel 9 is provided with a series of spaced horizontal slots 21 corresponding in number with the number of tenants to be served and through which the name cards of the respective tenants are visible, as indicated in Fig. 1 of the drawings. If desired at one end of each slot 21 a small opening 22 may also be provided in the panel through which the apartment number printed on the card may be seen. In spaced relation to the other end of each opening 21 a relatively wide and narrow opening 23 is formed through the panel, the metal struck from the panel remaining integrally connected with the outer side edge of said opening and being angularly offset from the plane of the panel to provide a card directing tongue 24.

When the reinforcing plate 12 is applied to the rear side of the panel and welded in connection therewith, by means of a suitable tool, circular openings are formed through the panel 9, corresponding in number with the number of the slots or openings 21, and in concentric relation with the openings 19 of the reinforcing plate, the metal at the edges of the panel openings being turned inwardly over and clinched upon the edges of the openings 19 as indicated at 25 in Fig. 4 of the drawings, thus providing additional securing means rigidly connecting the reinforcing plate with the panel. When the reinforcing plate has thus been applied and secured to the panel 9, the free ends of the card directing tongues 24 will be positioned substantially in the plane of the offset sections 16 of the reinforcing plate. It will

thus be apparent that after the completely assembled box or receptacle has been shipped by the manufacturer to the user, it is not necessary to remove the panel 9 in order to apply the name cards, since as shown in Fig. 3, the end of the name card may be readily inserted through the opening 23 and then forced laterally, the card being properly directed by the tongue 24 into the space between the rear face of the panel 9 and the offset part 16 of the reinforcing plate, said card being securely retained or supported by said plate section 16 behind the opening 21 and held against shifting movement so that the name will at all times be clearly visible.

It is another important feature of my present improvements to provide the reinforcing plate 12 with means whereby switch units for the operation of electric buzzers or call bells may be easily mounted thereon or removed therefrom as required. The manufacturer having ascertained the number of tenants to be served, cuts from each part 18 of the reinforcing plate rectangular portions each having one of the slots 20 therein and bends the same at right angles to the plane of said plate to provide the spaced arms 26, the said arms remaining integrally connected at one of their ends with the body of the reinforcing plate and being resiliently yieldable relative thereto. The switch unit indicated generally at 27 may be of various constructions, but as herein shown includes an insulating body having projecting parts 28 at the ends thereof of rectangular shape for engagement through the openings 20 in the arms 26. A spring contact member 29 has one of its ends bent and provided with openings in the spaced parts thereof receiving the insulating body of the switch, the said end of the contact being securely fixed to the switch body by the terminal screw 30. The other terminal screw 31 projecting from one side of the switch body provides a contact with which the free end of the spring contact member 29 is adapted to be engaged. For this purpose I provide a button 32 having an enlarged head 33 on one end engaged with the contact spring 29 and by which said button is normally urged outwardly through one of the circular openings in the panel 9. Thus, by pressing inwardly on the button, it will be understood that the two terminals 30 and 31 are electrically connected through the contact spring 29 to close the circuit.

By reason of the above construction, it will be readily seen that the manufacturer may fabricate the reinforcing plates with a comparatively large number of the sections 16 and 18 and secure the same to the panels by the welds 13. As the orders are received, the panels and the reinforcing plates may then be rapidly provided by simple additional operations with the necessary number of name card slots and switch unit support-

ing arms 26. The switch units need not be applied or mounted in position until the apartments are occupied, such switch units for the vacant apartments being contained 5 in the receptacle compartment closed by the panel 9. These switch units may be easily and quickly mounted upon the rear side of the panel by simply spreading apart the two arms 26 in order to enable the projecting 10 ends 28 of the switch body to be engaged through the openings 20 in the said arms. Also when an occupied apartment is vacated, the switch unit can be as readily removed from the rear side of the panel so that the 15 signal device cannot then be operated by mischievously inclined persons.

From the foregoing description considered in connection with the accompanying drawings, the construction, manner of use and 20 several advantages of my present improvements will be clearly and fully understood. It will, of course be apparent that the name card holding means as above described need not necessarily be used in connection with 25 a separate panel but might also as readily be applied to the tenant's door 7 of the mail box or to a part of the front plate 5 of the box structure. Although I have found the reinforcing plate structure embodying the 30 name card holders and the switch unit supporting means as above described to be capable of quantity production at relatively low cost and entirely satisfactory in practical use, it is nevertheless to be understood 35 that the essential features of the present disclosure are susceptible of embodiment in various other alternative structures, and I accordingly reserve the privilege of resorting to all such legitimate changes in the 40 form, construction and relative arrangement of the various parts as may be fairly incorporated within the spirit and scope of the invention as claimed.

I claim:

1. A panel for receptacles having an opening therein, a plate fixed to the rear side of said panel having a part extending over said opening and spaced from the rear face of said panel, and said panel at one end of said opening therein having an inwardly struck tongue constituting means for directing the insertion of a card from the front side of said panel into the space between said plate and the rear face of the panel. 45

2. As a new article of manufacture, a plate having an opening, a reinforcing plate attached to the first plate, the reinforcing plate having a section off-set from the plane thereof adjacent said opening to provide a space between the two plates, said section 60 being connected to the reinforcing plate except along one edge where it is separated therefrom to give admission to said space, the first plate having an opening adjacent the first opening with a portion adjacent 65 the last named opening extending into line with said off-set section.

3. A panel for receptacles having a plurality of spaced openings therein, a reinforcing plate substantially co-extensive with 70 said panel and secured to the rear side thereof, said plate having spaced parallel portions projected from the plane of the plate and in spaced relation to the rear face of the panel opposite the respective openings therein, and said panel having inwardly struck tongues at one end of the respective openings constituting means for directing a name card into the space between the rear face of 75 the panel and one of said parts of the reinforcing plate.

In testimony that I claim the foregoing as my invention, I have signed my name hereto.

SAMUEL HAMMER.
